LABEL MOISTENING AND/OR GUMMING DEVICE

Austin I. Voorhies, Miami, Fla.

Application September 17, 1948; Serial No. 49,795

2 Claims. (Cl. 91—51)

1

This invention relates to an improvement in label moistening and/or label gumming device and has for its object to provide a machine adapted to receive a previously gummed label and by a positive feed action to carry the label through the machine on suitable trackways for quickly and conveniently moistening the gummed side.

An object of the invention is to provide a machine having a pair of rollers for the combined feeding and application of moisture or adhesive to a single side of a label fed therethrough and to positively receive and pass the label through the machine without adhering to either the feed or to the applicator roller.

A further object of the invention resides in a moisture or adhesive applicator for labels or the like comprising a pair of contacting rollers for the combined feeding and application of moisture or adhesive to the underside of labels, etc., with a supporting runway of wires calculated to support the label after moistening and facilitating the removal thereof after moistening, together with suitable guards to prevent the label from following the rollers during its passage through the machine.

Another and important object of the invention is the extreme simplicity and efficiency of the device, constructed in a manner calculated to minimize the cost thereof, possesses few and simple parts requiring very little attention, may be quickly and conveniently disassembled for cleaning and will completely apply a coating of moisture or adhesive to the underside of a label or the like and project the said label to a position for convenient removal.

Other and important objects of the invention will be readily apparent during the course of the following description, reference being had to the accompanying drawings, wherein:

Figure 1 is a side elevation of a machine constructed in accordance with the invention,

Figure 2 is a plan view thereof,

Figure 3 is an end elevation thereof,

Figure 4 is a fragmentary section taken on line 4—4 of Figure 2,

Figure 5 is a transverse section taken on line 5—5 of Figure 1 and,

Figure 6 is an enlarged fragmentary section taken on line 6—6 of Figure 4.

Like numerals are employed to designate like parts throughout the several figures of the drawings.

Referring specifically to the drawings, the numeral 5 designates a base, having corner legs 6, 58

2

provided with pads 7. Preferably formed integral with the base 5, are oppositely arranged parallel side plates 8, flush with the outer longitudinal edge of the base and parallel therewith. The plates 8 are vertically arranged and transverse upstanding walls 9, integral with the plates and the base, form a fluid reservoir 10, adapted to contain water or adhesive. An applicator roller 11, preferably tubular, has a shaft 12, journaled in the plates 8, extending at one end for the reception of a driven gear 13. As clearly shown in Figures 3 and 5, the roller 11 has its outer surface knurled. A combined feed and pressure roller 14, corresponding in size to the roller 11 is superimposed in parallel relation above the roller 11, having contact therewith and provided with a shaft 15, journaled in the plates 8. The shaft 15 is co-extensive with the shaft 12 and carries a drive gear 16, meshing with the gear 13. A crank 20 arm 17 is employed to rotate the shaft 15 for returning the roller 14 in a clock-wise direction, while the meshing of the gears 16 and 13, causes the roller 11 to turn in a counter-clockwise direction. The surface of the roller 14 is preferably formed smooth. The shaft 15 of the roller 14 has been illustrated as being rotatably supported in open slots of the plates 8, for ease of removal and to permit full gravity engagement with the roller 14 throughout its length, but it will be obvious that the shaft may be journaled in any other convenient manner. The rollers 11 and 14 are held in spaced relation to the plates 8, by washers 18 to avoid frictional contact of the rollers with the plates.

Means are provided to properly feed the labels or the like through the machine, comprising a plurality of spaced parallel wires 19, extending for the full length of the machine. The wires 19, at the right end of the machine are detachably supported in notches 20 in a cross rib 21, formed upon a vertical transverse plate 22, integral with the base 5. The plate 22 is provided with an integral flat inclined table 23, the free end of which terminates adjacent the contacting points of the rollers 11 and 14. The wires 19 pass between the rollers 11 and 14 and have their opposite terminal ends detachably seated in notches 24, formed in ribs 25, formed integral with an upstanding transversely arranged plate 26. The wires 19 are inclined in parallel relation throughout their length corresponding to the inclination of the table 23 and have contact with the table surface throughout its length. Since it is essential for the proper moistening and/or gumming of labels, that the rollers have full contact with

the upper surface of the label, the roller 11 is circumferentially grooved for each of the wires 19 to a depth equal to the diameter of the wires, see particularly Figure 6. Thus, the label, being fed from the table 23 between the rollers, will have its gummed side, or side to be gummed exposed in contact to the knurled side of the roller 11 unobstructed by the wires 19. The wires 19, after engagement in their several notches, will be held suitably taut throughout their length.

It is highly important, that means be provided to prevent the labels from following the combined pressure and feed roller 14 during the feeding action. Therefore, to assure a proper passage of the label between the rollers, a plurality of wires 27, similar in number and diameter to the wires 19 and in vertical alignment therewith, engage in circumferential grooves 28 of the roller 14 to lie flush with the surface of the roller in use. The wires 27 extend outwardly from the contacting surface of the roller 14 and are inclined upwardly to pass about cross bars 29, after which they are inclined inwardly toward the roller 14 and again engage in the grooves 28. The bank of wires 27 with the wires 19 form a cage-like guard in wedge shape for facilitating the entry of the label between the rollers and a similar guard upon the discharge side to prevent the moistened or gummed label adhering to and following the roller 14, thus causing the label to pass freely upon the supporting wires 19. One bar 29 is grooved at 30 for the reception of a squeegee 31, engaging the side of the roller 14 for its entire width. The squeegee is inclined transversely to more readily conduct collected water or adhesive from the roller to be directed to the reservoir 10. As clearly shown, the roller 11 is partially submerged in the fluid of the reservoir and as the roller 11 revolves, fluid is picked up by the knurled surface to be brought into contact with the underside of the label. While the roller 11 has been shown as being knurled, it will be obvious that a plain surface roller may be employed and will function to a high degree of success.

In the use of the device, water having been introduced into the reservoir to the proper level and assuming that pre-gummed labels are to be moistened, a label is placed upon the table 23 with the gummed surface down. The crank is then rotated in a clock-wise direction to cause the entire surface of the roller 11 to be coated with water, after which the label is shoved to the point of engagement with the rollers. A continued rotation of the crank causes the label to be fed between the rollers 11 and 14. During its passage over the roller 11, water that has been picked up by the knurled surface is applied to the gummed side of the label and the label passes outwardly upon the wires 19, where it can be easily picked up with the fingers of the operator. The wires 19 are close enough together to prevent the label dropping therebetween, yet far enough apart to permit the insertion of the fingers beneath the label for removal. Any tendency of the label to adhere to and follow the roller 14 is prevented by the wire cage formed by the wires 27. Any water that has collected upon the surface of the roller 14 is removed by the squeegee 31 prior to its contact with the upper side of the label. Thus, the roller 14 at all times presents a relatively dry feed and pressure surface for the label. The operation of the device is identical when employing an adhesive in the reservoir 10 for use on unguaranteed labels.

5 While the machine has been illustrated for use in moistening gummed labels, it may readily be adapted to the moistening of strip gummed paper fed from a roll of such paper suitably mounted at one end of the machine to be fed between the rollers 11 and 14 as desired.

10 It will be seen from the foregoing that a very simple and efficient form of applicator has been provided for both gummed and ungummed paper labels. The structure is relatively cheap to manufacture, since the base and its associated parts can all be easily cast in a single unit from metal, plastic or other suitable material. The rollers may likewise be cast from plastic or other light inexpensive material, since wear thereon is negligible. All parts can be easily and quickly assembled or disassembled for purposes of cleaning or replacement. The device will quickly and completely apply an even coat of moisture over the 15 entire surface of the label by a single passage of the label between the rollers, leaving no bubbles or dry spots so commonly encountered by the usual hand applicators now in use and presents the label ready for application without in any way soiling the printed side.

20 25 It is to be understood, that the invention is not limited to the precise arrangement shown, but that it includes within its purview, whatever changes fairly come within either the terms or the spirit of the appended claims.

30 Having described my invention, what I claim is:

1. A label moistening machine of the character described comprising a base having vertically arranged integral end plates, a fluid reservoir 35 formed on the base intermediate its ends, the reservoir defined by transverse upstanding walls and vertically arranged parallel side walls, a fluid pick-up roller journalled transversely of the machine with its lower side extending into the reservoir, a shaft for the rotatable support of the roller, the side walls provided with journal openings for the reception of the shaft, a gear fixed upon the end of the shaft outwardly of the side wall, the roller being knurled entirely over its 40 cylindrical surface and grooved circumferentially, with the grooves being equidistantly spaced, one end plate provided with an integral feed table projecting inwardly toward the upper surface of the roller at an incline, a plurality of parallel wires extending from end to end of the machine and angularly disposed at an angle corresponding to the angle of the table and in parallel contact with the surface of the table, means for removably securing the terminal ends of the wires for 45 maintaining the wires taut, the said wires being spaced corresponding to the spacing of the grooves of the roller and normally lying in the grooves, the grooves having a depth corresponding to the diameter of the wires whereby the wires are flush with the upper surface of the roller, a combined pressure and feed roller superimposed above and in parallel contacting relation to the pick-up roller, the cylindrical surface of the feed roller being circumferentially grooved in a manner identical with the pick-up roller in depth and spacing, with the grooves aligned, a shaft for the rotatable support of the feed roller, the side plates being slotted for the reception of the shaft, a pair of bars supported by the side 50 plates in parallel relation to the feed roller, with the bars being arranged upon opposite sides of the feed roller and below the axis thereof, a plurality of wires trained about the bars and the feed roller, with the last named wires being relatively taut and engaging in the grooves of the 55 60 65 70 75

feed roller at top and bottom thereof, the last named wires providing a wedge shaped guard for the feeding of labels to the rollers and a wedge shaped guard upon the opposite side of the rollers and a squeegee carried by one of the bars and engaging the side of the feed roller and gear means carried by the shaft of the feed roller outwardly of the side plates for driving engagement with the first named gear and a crank for rotat-

ing the feed roller shaft.

2. A label moistening machine that comprises a rigid flat base having upstanding end plates and upstanding parallel side plates, the side plates being arranged substantially intermediate the ends of the base, integral transverse and upstanding walls formed on the base and connecting the side plates, the walls and side plates forming a fluid reservoir, one end plate provided with an integral inwardly extending and downwardly inclined feed table, with the inner end of the table partially overlying the reservoir, a fluid pick-up roller arranged transversely of the machine and centrally disposed with respect to the reservoir, a shaft for the rotatable support of the roller journaled in the side plates with one end of the shaft extended for the reception of a driven gear, the said roller having one longitudinal side extended into the reservoir, the entire cylindrical surface of the roller being knurled and circumferentially grooved at equidistantly spaced points over its surface, a plurality of feed and support wires extending for the full length of the machine and having their opposite terminal ends detachably connected to the end plates for maintaining the wires in taut position, the wires being parallel and spaced in accordance with the spacing of the grooves of the roller and normally recessed in the grooves to be flush with the uppermost surface of the roller, the wires being inclined at an angle identical with the angle of the table and in full contact with the table for its full length, a combined pressure and feed roller identical in size to the pick-up roller superimposed over the pick-up roller in parallel contacting relation for its full length, a shaft for the rotatable support of the feed roller journaled in vertical parallel slots formed in the side plate, the feed roller being freely verti-

cally moveable in the slots for gravity engagement with the pick-up roller, the cylindrical surface of the feed roller being smooth and provided with equidistantly spaced circumferential grooves corresponding in spacing and depth to the grooves of the pick-up roller and aligned therewith, a parallel bar arranged outwardly of the sides of the feed roller and below the center line of the roller, a plurality of wires trained over the roller and bars with the wires having a seating in the grooves of the feed roller over its upper portion and over its point of contact with the pick-up roller, the seating of the wires in the grooves of the rollers permitting of a full and uninterrupted contact of the rollers for their entire length, a squeegee carried by one of the bars for the full length of the feed roller, the bars being fixed in the side plates, the first and second named group of wires being in longitudinal alignment, the training of the second named wires about the feed roller and the bars providing a wedge shaped feed opening for directing the labels between the rollers, while the training of the second named wires about the bar on the opposite side of the feed roller provides a wedge shaped guard against the label adhering to the feed roller upon the discharge side, the said first named wires serving to support the label after being discharged from the rollers, a drive gear carried by the shaft of the feed roller to be meshed with the gear of the pick-up roller and a crank for driving the shaft of the feed roller.
